United States Patent Office

Des. 204,711
Patented May 10, 1966

204,711

BOTTLE

James E. Plummer, Toledo, Ohio, assignor to Owens-Illinois Inc., Toledo, Ohio, a corporation of Ohio

Filed Oct. 23, 1965, Ser. No. 87,860

Term of patent 14 years

(Cl. D58—8)

FIG. 1

FIG. 2

FIG. 3

FIG. 1 is a front elevational view of a bottle showing my new design.

FIG. 2 is a side elevational view thereof.

FIG. 3 is a top plan view thereof.

The back and side not shown are the same as the front and side shown.

The characteristic features of this design reside in the configuration shown in full lines on the drawing.

I claim:

The ornamental design for a bottle substantially as shown and described.
